UNITED STATES PATENT OFFICE

132,568

DESIGN FOR A CIGARETTE DISPENSER

Edward Howell Bernstein, Melrose Park, Pa.,
assignor to Lewis P. Weil, Philadelphia, Pa.

Application January 29, 1942, Serial No. 105,493

Term of patent 7 years

To all whom it may concern:

Be it known that I, Edward Howell Bernstein, a citizen of the United States, residing at Melrose Park, in the county of Montgomery, State of Pennsylvania, have invented a new, original, and ornamental Design for a Cigarette Dispenser, of which the following is a specification, reference being had to the accompanying drawing forming part thereof.

Fig. 1 is a side elevational view of a cigarette dispenser showing my design.

Fig. 2 is a front elevational view of same.

The opposite side of the article in Fig. 1 is substantially the same as that shown in said Fig. 1.

I claim:

The ornamental design of a cigarette dispenser, as shown and described.

EDWARD HOWELL BERNSTEIN.
